UNITED STATES PATENT OFFICE.

WILLIAM H. GENUNG, OF MADISON, OHIO.

REVOLVING SHOW-FRAME.

SPECIFICATION forming part of Letters Patent No. 349,883, dated September 28, 1886.

Application filed July 30, 1885. Serial No. 173,046. (No model.)

To all whom it may concern:

Be it known that I, WILLIAM H. GENUNG, of Madison, in the county of Lake and State of Ohio, have invented a new and Improved 5 Revolving Show-Frame, of which the following is a full, clear, and exact description.

The object of my invention is to provide a simple, effective, and inexpensive show-frame, adapted to advantageously display merchandise in store-windows or on counters.

The invention consists in a show-frame comprising a hollow post fitted to a spindle journaled on a suitable base containing mechanism, by which the spindle and post are rotated, 15 said post carrying hinged arms and cords, on which is fastened a fabric cover, to which goods may be attached. The post has fitted in it a series of elastic and radially-adjustable arms, on which light fabrics may be hung for 20 show, and at the same time to offer more or less resistance to the air, to regulate the speed of rotation of the frame, all as hereinafter fully described and claimed.

Reference is to be had to the accompanying 25 drawings, forming part of this specification, in which similar letters of reference indicate corresponding parts in all the figures.

Figure 1 is a sectional side elevation of my improved show-frame. Fig. 2 is a plan view 30 thereof with the cover of the frame removed, and the fabrics removed from the upper arms. Fig. 3 is an enlarged sectional view of the upper end of the hollow post of the show-frame with the upper elastic arms lowered into the 35 post; and Fig. 4 is a plan view of the flanged sleeve and a part of one of its arms.

The letter A indicates the base or support 40 of the show-frame, said base being made, preferably, in the form of a round shallow case or 45 box, in which any approved mechanism actuated by a spring or weight is contained, said mechanism being arranged to rotate an upright spindle, B, which is journaled in a bearing or hollow post, a, rising from the base A. (See Fig. 1.)

To the spindle B is fixed the lower end of the light tubular post C of the show-frame, which post may have any desired height.

On the post C is fitted loosely the sleeve D, 50 which has an upper flange, d, to which a number of light arms, E, are pivoted at d', said

arms having inner extensions, e, which normally lie on top of the flange d and prevent lifting of the arms above a horizontal position by the cords F, which are attached at their 55 one ends to the outer ends of arms E, and at their other or upper ends to a plate or collar, G, which is fixed to post C near its top. Cords F connect the outer ends of the arms E to each other. (See Fig. 2.)

The sleeve D, arms E, plate G, and cords F F' form a light pyramidal or cone-shaped structure which revolves with the post C.

A spring, H, fixed at its upper end to the post C, and having an inturned lower end, 55 which stands above the sleeve D, prevents upward slipping of the sleeve on the post, and holds arms E properly extended therefrom.

I stretch any suitable cloth or semi-transparent fabric between the cords F F', as at I, 70 Fig. 1, and inside the fabric covering is or may be fastened on the post C, a shelf or support, J, on which lamps or lights of any approved kind may be placed, so that goods pinned or otherwise fastened to the covering I will show 75 at night to better advantage, and the show-frame itself will have a more attractive appearance.

The letters K L indicate, respectively, long 80 and short elastic arms or rods, made preferably of spring wires or rods and bunched near their lower ends, where they are tied together firmly by a wire or cord, as at M, Figs. 1 and 3.

The arms K L are shaped or bent so that 85 they normally will curve upward and outward from each other above the tie wire or cord M, and at their outer ends the arms K L will preferably be formed as hooks k l, respectively, on which fabrics may be hung.

Below the tie wire or cord M the arms K L, 90 three or more of them, will be bent outward in curves, as at m, so that when the arms are placed within the post C, their curved ends m will exert a pressure against the interior face of the post, 95 to hold the arms in the post when their outer ends radiate from the post, in position to receive the light fabrics N O, which may be hung on the body parts and on the end hooks of the arms, as shown in Fig. 1. The friction of the 100 lower ends, m, of the arms on the post is supplemented by the outward pressure of the arms

on the upper extremity of the post, to prevent slipping of the arms from or along the post, so that when the arms are pushed farther into or drawn out farther from the post, to shorten or 5 lengthen the parts of the arms, which spread out from the top of the post, the arms will stay in the desired position.

I have found by experiment that light fabrics, such as handkerchiefs N O, when suspended on the arms at the head of the show-frame, and because of the resistance they offer to the air as the show-frame top revolves, constitute an effective speed-regulator to maintain a quite uniform rotation of the show-frame 15 post and its connections best calculated for the most advantageous display of the goods on the frame.

It is evident that by drawing the arms K L farther from the post C, the fabrics N O, or the 20 latter only, will project farther from the post, so as to describe a larger circle in the air, and consequently offer greater resistance to the air, and cause the show-frame to rotate more slowly, and when the arms are pushed farther into 25 the post C the speed of the show-frame will increase, due to the smaller circle traveled by the fabrics and their consequent reduced resistance to the air.

I show four elastic arms, K, and four arms, 30 L; but any desired number of arms may be employed.

The spring H may be pressed in and the sleeve D be run up on the post C at any time to fold the lower arms, E, downward around 35 the post until the arms strike the shelf J, or, if preferred, the shelf may be made in two parts, allowing its removal, so that the arms may fold closely to the post, and the elastic arms K L may be slid downward entirely within 40 the post, as in Fig. 3, to allow the entire show-frame to be packed in small space for transportation, or for storage when out of use.

Having thus fully described my invention, I claim as new and desire to secure by Letters 45 Patent—

1. A show-frame comprising a base, A, a spindle, B, journaled therein, mechanism in the base for rotating the spindle, a post, C, fixed to the spindle, a sleeve, D, arms E e, hinged thereto, cords F F', fabric covering I, spring 50 H, and elastic arms K L, tied together at M, and having diverging ends m, and fitted in post C, all substantially as herein set forth.

2. The combination, in a show-frame, of the base A, a spindle, B, journaled therein, mechanism in the base for rotating the spindle, a post, C, fixed to the spindle, the sleeve D, arms E e, hinged thereto, the spring H, cords F F', and fabric covering I, substantially as herein set forth. 55

3. In a show-frame, the sleeve D, fitted to slide on the post C, and having arms E, hinged to its flange d at d', and said arms having ends e, overlapping the flange d, and the spring H, combined for operation substantially as herein set forth. 60

4. The combination, in a revolving show-frame, and with the actuating-motor thereof, of a spindle, B, connected with the motor, a hollow post, C, rotated by said spindle, and a series of elastic arms, K L, tied together at or near one end and fitted adjustably in the post C, substantially as herein set forth. 70

5. The combination, in a revolving show-frame, and with the actuating-motor thereof, of a spindle, B, a post, C, rotated thereby, a series of arms, K L, tied together at or near one end and fitted in the post C, and fabrics, as at N O, hung on said arms, substantially as herein set forth. 75

6. In a show-frame, the combination, with the hollow rotating post C, of a series of elastic curved arms, as at K L, tied together at M, and bent divergently at their lower ends, as at m, to take frictional hold in the post, substantially as herein set forth. 80
